UNITED STATES PATENT OFFICE

JOSEPH MÜLLER, OF DEANS, NEW JERSEY

VALVE

Application filed February 24, 1930. Serial No. 430,803.

This invention aims to provide a novel means whereby one valve may be made to open or close, responsive to pressure changes, a second valve being opened, when the first valve closes, thereby to afford drainage: the device being of peculiar utility in connection with a water regulator which governs the cooling water which passes to the condenser of a refrigerating machine. Although a refrigerating machine has been mentioned, it will be understood that the device hereinafter described may be used for any purpose to which it is adapted.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawing, the device is shown in a single sectional figure, wherein parts appear in elevation.

The numeral 1 marks a valve casing having an inlet 2 and an outlet 3. The casing 1 is supplied with a seat 4 located between the outlet 3 and the inlet 2. The seat 4 has an opening 5.

A closure 6 is threaded into the lower portion of the valve casing 1. The closure 6 has a tubular guide 7 in which a hollow valve 8 is mounted to reciprocate. The valve 8 is adapted to cooperate with the seat 4, to open and close the aperture 5. A compression spring 9 is housed within the valve 8 and the guide 7. The function of the spring 9 is to cause the valve 8 to close against the seat 4. The valve 8 has a boss 14, which may be a short screw threaded into the top of the valve.

The casing 1 is supplied with an upstand-

ing nipple 10 having a lateral drain 11. A seat 12 is located within the nipple 10.

A cap 15 is threaded upon the upper end of the nipple 10 and carries a gland 16. A valve 23 cooperates with the seat 12. A thimble 18 is threaded through the valve 23 and has a flange 22 against which the valve is engaged. A gland 24 is mounted on the upper end of the thimble 18. A plunger 17 is slidable in the gland 16. The plunger 17 slides through the gland 24 and through the thimble 18. A nut 19 and a lock nut 19a are threaded on the plunger 17, at 20, and form a shoulder adapted to engage the lower end of the thimble 18, to open the valve 23, it being possible to adjust the nuts 19 and 19a along the plunger 17. The lower end of the plunger 17 is adapted to cooperate with the boss 14 on the valve 8. A spring 25 is located in the nipple 10. One end of the spring 25 abuts against the cap 15, and the other end of the spring acts on the valve 23 to hold the valve yieldably seated, the part 25 being a spring which operates compressively.

The numeral 26 designates a head made up of plate-like members 27 and 28, held together by securing elements 29, a resiliently yieldable diaphragm 30 being held between the members 27 and 28 of the head 26. The head 26 has a chamber 32 formed partly in the member 28 and partly in the member 27, the diaphragm 30 extending across said chamber. The member 28 of the head 26 has a pressure inlet 31 communicating with the chamber 32 on one side of the diaphragm 30. The head 26 is carried by the valve casing 1 through the instrumentality of posts 33.

The member 27 of the head 26 has a recess 34, in which a pressure piece 35 is slidably mounted, the pressure piece engaging the diaphragm 30. The pressure piece 35 has a stem 36 which extends downwardly through the member 27 of the head 26.

The numeral 37 marks a slide, in the form

of a cross bar, carried for reciprocation on the posts 33. The slide 37 has an opening 38, which is enlarged near its upper end to form a shoulder 39. A stud 40 engages the 5 lower end of the stem 36 of the pressure piece 35, and has a reduced end 41 located in the opening 38 of the cross bar 37. The reduced portion 41 of the stud 40 forms a shoulder 42 which cooperates with the shoulder 39 in 10 the slide 37. The upper end of the plunger 17 is threaded for adjustment into the stud 40 and is held in adjusted positions by means of a lock nut 43. Compression springs 44 surround the posts 33. The upper ends of 15 the springs 44 engage the cross bar or slide 37, and the lower ends of the springs 44 engage washers 45 which are supported by nuts 46 threaded on the posts 33, adjustable abutments for the lower end of the springs 44 thus 20 being provided.

In practical operation, so long as there is a predetermined pressure at the inlet 31, the diaphragm 30, the pressure piece 35, its stem 36, the stud 40, and the plunger 17, cooperate 25 to hold the valve 8 open, as shown in the drawing, the valve 23 being closed by the action of the spring 25. Under such circumstances, the cooling water or other flowing medium can enter by way of the inlet 2, and 30 leave by way of the outlet 3, an observation which will be understood readily when the opening 5 and the valve 8 are noted.

When the pressure is released in the inlet 31, then the diaphragm 30 will move upwardly, the part 37 being carried upwardly by the springs 44, the spring 9 closing the valve 8 on the seat 4, and the plunger 17 being carried upwardly by the slide or cross bar 37. When the plunger 17 moves upwardly, as aforesaid, the nut 19 engages the 40 lower end of the thimble 18 and raises the valve 23 to an open position, whereupon, water can flow backwardly from the member 3, into the nipple 10 and away through the drain 11. The water thus can be drawn out of condensers or similar machines, and difficulties arising out of freezing water may 45 be avoided.

Having thus described the invention, what 50 is claimed is:

In a device of the class described, a valve casing having an inlet and an outlet, the casing being supplied with a seat located between the inlet and the outlet, the casing being 55 supplied with a projecting nipple closed at its outer end, the nipple having a drain, and there being an opening at the inner end of the nipple which communicates with the valve casing on one side of the seat, a first valve in the casing, spring means for closing the first valve casing, spring means for closing the first valve against the first-specified seat, in one direction, a second valve in the nipple, spring means in the nipple for closing the second valve in an opposite direction with re-

spect to the opening, a plunger slidable in the outer end of the nipple and engageable with the first valve to open the first valve when the plunger moves in one direction, the plunger passing through the opening and having means for opening the second valve when the plunger moves in an opposite direction, and fluid pressure actuated means mounted on the valve casing and coacting with the plunger to open the first valve.

In testimony that I claim the foregoing as my own, I have hereto affixed my signature.

JOSEPH MÜLLER.
